EDWARD T. COVELL, OF BROOKLYN, NEW YORK,

Letters Patent No. 96,889, dated November 16, 1869; antedated November 10, 1869.

IMPROVEMENT IN BAILS AND HANDLES FOR PAILS, &c.

The Schedule referred to in these Letters Patent and making part of the same

To all whom it may concern:

Be it known that I, EDWARD T. COVELL, of the city of Brooklyn, State of New York, have invented a new and improved Attachment of Guards to Bails or Handles of Cans, Pails, and other vessels; and I do hereby declare the following to be a full and exact description thereof, reference being had to the accompanying drawings, forming a part of this specification, in which—

Figure 1 is a side view, and

Figure 2 a plan of a wooden guard for metallic handles.

Figure 3, a perspective view of the same when secured to the handle;

Figure 4, a top view of handle in fig. 3;

Figure 5, a transverse section in the line *xx* of fig. 3;

Figure 6, a sectional view of a modification of the mode of combining the clamp with the guard;

Figure 7, a longitudinal section in line *yy* of fig. 6; and

Figure 8, a sectional view, illustrating a complete double guard, divided to admit the handle, and united and secured by means of outer metallic clamps or clasps.

The nature of my invention consists in the attachment of suitable guard-pieces to metallic handles or bails, to perfect and complete the same, by means of metallic clamps, as hereinafter fully described.

The customary mode of attaching guards to handles or to bails has been to pass the wire of the bail through a longitudinal perforation in a cylindrical guard-piece.

If the guard becomes broken, the handle or bail must be removed to replace it.

My invention admits of the ready attachment of a guard to the handle or bail, without removing the latter, and it is much cheaper in its manufacture and attachment than the old form.

The guard which I use is a semi-cylindrical or rounded piece A, of any suitable material, by preference, however, of wood, having a flat upper surface bevelled at its ends, as shown in fig. 1, to fit the straight or flattened portion of the handle or bail B, and notched, as illustrated in fig. 2, to receive and embrace the same, and thus be prevented from turning thereon.

This guard-piece A, so fashioned, is securely held

in place upon the under side of the metallic handle or bail B, by means of a clamp C, of metal, so bent as to partially embrace the metal of the handle or bail B, extending over the upper surface of the guard A, (see fig. 4,) and, curving over its edges closely, pass down far enough on each side thereof to embrace and uphold the same, as illustrated in fig. 5.

A slipping of the guard A, in its clamp-plate C is prevented, either by means of small tacks or by indentations of the plate C into the guard-piece, as shown in fig. 4, or else by cutting a recess in the guard-piece, as shown in fig. 7, to receive the clamp-plate.

The hold of the clamp-plate upon the guard-piece may be made yet more secure by cutting grooves *dd*, fig. 7, in the sides of the guard-piece A, to receive the edges of the clamp C, which are in such case pressed down into the same. (See fig. 6.)

Instead of using simply a semi-cylindrical guard-piece, A, as just described, I contemplate securing a complete double-oval cylindrical guard upon the metallic handle or bail B, by means of outer clamp-plates or clasps.

In this case the oval or cylindrical guard E, fig. 8, is divided longitudinally, and the two halves are secured by means of outer clamp-plates *ff*, bent to conform thereto, and whose edges pass into grooves cut into the sides of each division, as illustrated in fig. 8.

The clasps or clamp-plates may be cast or swaged, or else cut out of sheet-metal.

Having thus fully described my invention,

I claim therein as new, and desire to secure by Letters Patent—

1. The combination of a guard or guard-piece, A, with the handle or bail of a can, pail, box, or other vessel, to form a handle for the same, by means of metal clamp-plates, partially embracing the wire and guard, substantially as herein set forth.

2. The combination of a longitudinally divided and flattened or cylindrically or polygonally-shaped guard E, with a metallic bail, B, and with metal clamps to secure and unite the two divisions of the guard, substantially in the manner herein set forth.

E. T. COVELL.
